UNITED STATES PATENT OFFICE.

CHARLES SEIGFRIED ANDERSON, OF MINNEAPOLIS, MINNESOTA, ASSIGNOR OF ONE-FOURTH TO FREDERICK J. KNORR, OF MINNEAPOLIS, MINNESOTA.

PISTON-MOLD-MAKING DEVICE.

1,262,906.

Specification of Letters Patent. Patented Apr. 16, 1918.

Application filed March 16, 1916. Serial No. 84,601.

To all whom it may concern:

Be it known that I, CHARLES SEIGFRIED ANDERSON, a citizen of the United States, residing at Minneapolis, in the county of 5 Hennepin and State of Minnesota, have invented certain new and useful Improvements in Piston-Mold-Making Devices; and I do hereby declare the following to be a full, clear, and exact description of the invention, such as will enable others skilled 10 in the art to which it appertains to make and use the same.

My invention has for its object to provide an improved molding apparatus especially 15 adapted for casting pistons; and to such ends, generally stated, the invention consists of the novel devices and combinations of devices hereinafter described and defined in the claims.

20 The special object of the invention is to provide a piston-mold making device which is serviceable for forming molds used in the casting of pistons for internal combustion engines, such as is used in automobiles 25 and auto-trucks. The pistons of engines of the above character, as now found in the market, vary in diameter from two and three-fourth to five inches, the variations being usually but one-fourth inch but sometimes but one-eighth of an inch. Pistons of 30 the same diameter vary greatly in length and they also vary in respect to the diameter and location of their wrist pin bosses.

35 My invention provides a device for making molds whereby pistons of a given diameter may be cast in all of their varying different lengths, and also provides for the desired variation in the location and diameter of the wrist pin boss in the different lengths 40 of pistons.

This is accomplished by providing a piston mold pattern that is adjustable as to length and by providing a piston mold core box that is also adjustable in length and is 45 provided with interchangeable or detachable and adjustable wrist pin boss patterns. By the use of such a device, in practice I have found that by my invention I not only very greatly decrease the cost of casting pistons, 50 especially for repair work, but make it possible at very short notice and without requiring the making of wooden patterns, to cast the pistons in the various different lengths, as may be required. Of course, for 55 pistons of different diameters, different pat-

tern sections must be provided, but even in this instance, a good many of the parts used are interchangeable or usable with the sections for casting pistons of different diameters.

60 In the accompanying drawings which illustrate the invention, like characters indicate like parts throughout the several views.

Referring to the drawings: 65 Figure 1 is a side elevation showing the piston mold pattern;

Fig. 2 is a vertical section taken centrally through the same;

Fig. 3 is a horizontal section taken on the 70 line $x^3 x^3$ of Fig. 2;

Fig. 4 is a plan view of the mold core box, some parts being sectioned and some parts being broken away;

Fig. 5 is a section taken on the line $x^5 x^5$ 75 of Fig. 4; and

Fig. 6 is a section taken on the line $x^6 x^6$ of Fig. 4.

Referring first to the piston pattern shown in Figs. 1, 2 and 3, the numeral 1 80 indicates the core print of the pattern and the numerals 2, 3 and 4 indicate the central pattern sections for forming that portion of the mold which forms the exterior surface of the piston. The sections 2 and 3 85 have solid heads at their ends and these heads are formed with axial hubs 2^a and 3^a, respectively. The intermediate section 4 has a hub 4^a connected to the cylindrical shell by radial spokes 4^b. A bolt 5 is passed 90 through the core print 1 and the hub 2^a of the section 2 and into the hub 3^a of the section 3 and its threaded end is engaged with a sleeve-like nut 6 rotatably mounted in the hub 3^a and provided at its outer end with a 95 shoulder that clamps the head of the said section 3, thereby locking the several sections 2, 3 and 4 together in axial alignment and with their cylindrical outer surfaces forming a continuous cylinder. The core 100 print 1 projects very considerably radially outward of the cylindrical surface of the sections 2, 3 and 4, and may be used in connection with cylinder-forming sections that vary considerably in diameter. Obviously, 105 the length of the cylinder may be varied by varying the width of the intermediate section 4. In forming the cavity in the sand, the pattern is set with its axis vertical and with the print 1 on top, and with the upper 110

surface of the print on the "parting" of the flask. The said print 1 will leave a cavity for the reception of the anchoring flange of the core to be hereinafter described.

5 The device for forming the piston core is illustrated in Figs. 4, 5 and 6, and, as shown, it is made to form only one-half section of the core. Otherwise stated, the core-forming sections are semi-cylindrical, and 10 in the use thereof, two half cores will be made and these two half cores will be stuck together to make a complete core. When it is desired to make a complete core in one operation, two of the devices shown may be 15 put together, but in this instance, the core box will be set with its axis vertical and the top head plate, hereinafter described, will not be required.

Describing the core box, as shown, the 20 numerals 7 and 8^a indicate so-called head plates. The numeral 8 indicates a semi-cylindrical section for forming the core print anchoring flange which is adapted to fit the seat made by the core print 1 of the 25 pattern illustrated in Figs. 1, 2 and 3. The numerals 9, 10 and 11 indicate semi-cylindrical sections for forming the body of the core print. These sections 9, 10 and 11 are preferably formed with internal ribs for 30 producing corresponding depressions in the sand whereby reinforcing ribs are produced in the interior of the piston. The wrist pin boss patterns 12 are detachably and adjustably secured to the section 10 by means of 35 screws 13 which work through slots 14 in the said section 10. The said boss patterns 12 are provided with projecting ribs that overlap the section 11. The said sections 9, 10 and 11 may be made in different widths, 40 and the wrist pin boss patterns 12 may be attached to the sections 10 that vary in width, and furthermore, in the arrangement illustrated, are capable of limited adjustment in respect to the said section 10. The 45 said sections 9, 10 and 11 are provided with outwardly projected lugs 15 and clamping bolts 16 are passed through the head plate 8^a and through the several alined lugs 15 and are screwed into long sleeve-like nuts 50 17 that are passed through the head 7 and section 8 and are provided at their outer ends with shoulders counter-sunk into said head plate.

As is evident, by providing sections 9, 10 55 and 11 that vary the width, the cores for pistons of different length may be made. The distance between the inner faces of the head plates 7 and 8^a should be, say one-fourth of an inch more space than the distance 60 between the inner face of the core print 1 and the face of the head of the section 3 of the cylinder pattern, so as to provide, in the sand, a space for forming the head of the piston. Obviously, when a core 65 made in the core box described, is placed

within the cavity made by the piston pattern and with the anchoring flange of the core seated in the impression made by the core print 1, the exact cavity required for casting the piston is formed in the mold. Preferably, all of the parts, both of the pattern and of the core box, are made of metal, thereby insuring greater accuracy. In practice, I have found that by the use of the above device, pistons having very thin and 75 accurately formed walls may be made, all without requiring any great skill in the workman.

In the device described, the head plates, clamping bolts and wrist pin lug patterns 80 may be used with sections 9, 10 and 11 of different diameter, and even the section 8 may be used where the variation in diameter is not great. Very great economy in patterns required in making various different 85 sizes of pistons is therefore effected by the use of this device.

What I claim is:

1. A piston mold making device comprising a sectional longitudinally extensible and 90 contractible piston pattern and a sectional longitudinally extensible and contractible core box, the latter, in its various adjustments, being slightly shorter than the former, whereby space for the casting of the end 95 wall of the piston is formed in the mold.

2. A piston-mold making device comprising a sectional longitudinally extensible and contractible piston pattern and a sectional longitudinally extensible and contractible 100 core box, the latter, in its various adjustments, being slightly shorter than the former, whereby space for the casting of the end wall of the piston is formed, the said pattern having a core print at one end and the 105 said core box having a flange forming section for forming on the core an anchoring flange to fit the impression made by the core print of said pattern.

3. A core box made up of a plurality of 110 sections arranged to be put together in different ways to form cores for pistons of different lengths, means for detachably holding the said sections together, and wrist pin patterns detachably secured to the interior 115 of certain of the said sections.

4. A core box made up of a plurality of sections arranged to be put together in different ways to form cores for pistons of 120 different lengths, head plates applied to the ends of the outer sections, and means for detachably holding said head plates and sections together.

5. A core box made up of end and intermediate sections arranged to be put together 125 in different ways to form cores for pistons of different lengths, wrist pin patterns detachably secured to one of the intermediate sections, head plates applied to the outer ends of the outer sections, and means for 130

detachably connecting said sections and head plates.

6. Molding apparatus for piston - mold making comprising a pair of end sections, a multiplicity of central sections each of different character, and means for interchangeably connecting any of said central sections in position between said end sections, said connecting means being adjustable to fit any 10 length of central section.

7. Molding apparatus for piston - mold making comprising a plurality of sections, some of said sections being of fixed character and some of differing character, means 15 for connecting the sections of fixed character interchangeably with a section of differing character, wrist pin boss patterns, and means for adjustably connecting said boss patterns with the sections of variable 20 character.

8. Molding apparatus for piston - mold making comprising a pair of complementary mold-forming members each consisting of a pair of end sections of fixed length and an intermediate section, at least one of said end sections being of a different length from the corresponding section of the other member, the intermediate sections being of the same length, and means for interchangeably holding said intermediate and end sections in 25 position in each member whereby the intermediate sections may be changed to vary, at will, the length of piston to be formed in the molds made in said apparatus.

In testimony whereof I affix my signature 30 in presence of two witnesses.

CHARLES SEIGFRIED ANDERSON.
